UNITED STATES PATENT OFFICE.

FREDERICK F. HASKELL, OF MEDFORD, MASSACHUSETTS, ASSIGNOR TO CAMBRIDGE NOVELTY COMPANY, OF CAMBRIDGE, MASSACHUSETTS, A CORPORATION OF MASSACHUSETTS.

BOW-HOLDER.

1,076,423.

Specification of Letters Patent. Patented Oct. 21, 1913.

Application filed June 21, 1912. Serial No. 705,083.

To all whom it may concern:

Be it known that I, FREDERICK F. HASKELL, a citizen of the United States, and a resident of Medford, in the county of Middlesex and State of Massachusetts, have invented certain new and useful Improvements in Bow-Holders, of which the following is a specification.

This invention relates to holders adapted 10 to be secured to a coiffure or other support and to hold in place on such support an ornament such as a ribbon bow, the holder being adapted to detachably confine the bow and to enhance the appearance of the 15 bow or other article when in use.

The invention consists in the improvements which I will now proceed to describe and claim.

Of the accompanying drawings: Figure 20 1 represents a perspective view of a bow holder embodying my invention. Fig. 2 represents a section on line 2—2 of Fig. 1. Fig. 3 represents a perspective view showing end portions of the wire clasp.

25 The drawing represents the device on an enlarged scale.

The same reference characters indicate the same parts in all the figures.

In the drawings: 12 represents a base 30 plate which as here shown is a part of a barrette and is provided with inwardly projecting ears 13 at one end in which is pivoted a hair pin 14, the free ends of which are adapted to be engaged with catches 15 35 at the opposite end of the base plate.

The base plate and its adjuncts above described are adapted to be secured to a coiffure in a manner well understood. The base plate may, however, be otherwise 40 formed and secured by other means to the support. The base plate is provided with a pair of outwardly projecting ears 18 having perforations 17 which constitute bearings. The base plate is also provided with 45 a pair of outwardly projecting ears 18 having notches 19, the notched ears being adapted to serve as detents or catches.

With the base 12 and its ears co-operates 50 a resilient clasp composed of a single length of wire having the portions 20, 21, 22 and 23 all formed by suitably bending the wire to the shape represented by Figs. 1, 2 and 3. The portions 22 are near the ends of the wire and are in alinement with each other, 55 these parts constituting trunnions which are journaled in the orifices 17 of the ear 16.

The portions 21 constitute resilient arches connecting the trunnions 21 with the portion 20, said portion having a transverse neck between the portions 21 and adapted 60 to engage the notches 19 of the ears 18. The portions 23 constitute the extremities of the wire and are bent practically at right angles to the trunnions 22, said portions 23 constituting guards which prevent the withdrawal of the trunnions from the ears 16. It will now be seen that when the clasp is in the position shown by dotted lines in Fig. 2, a ribbon or other ornament may be suitably fashioned to be contained in the curve 70 of the portions 21 and that said ornament may be secured in place by moving the clasp to the position shown in full lines and springing the bar portion 19 into engagement with the notched ears 18. The portions 23 form tension producing abutments which coöperate with the base plate 12, when the clasp is moved to closed position, so that by the time the portion 20 engages the hooks 18 an increased tension is brought on member 75 21. The bow is thus securely held until the portions 21 are flexed inwardly to disengage the portion 20 from the ears 18. The base may be formed and adapted to be applied to a shoe or other article to which a 80 bow or other ornament is to be attached.

I claim:

1. A bow holder comprising a base plate provided with spaced apart ears and spaced apart detents, and a clasp formed of a single wire bent at its middle portion to form a transverse detent-engaging member and parallel resilient arches, the ends of said arches opposite said detent-engaging member being pivotally mounted in said ears, the extremities of said wire being so bent as to engage said plate to form tension-producing abutments when the detent-engaging member is in engagement with said detents. 95

2. A bow holder comprising a base plate 100 provided with spaced apart ears and spaced apart detents, and a clasp formed of a single wire bent at its middle portion to form a transverse detent-engaging member and parallel resilient arches, the ends of said arches 105 opposite said detent-engaging member being bent at right angles to form trunnions which are passed through said ears, the extremities of said wires being so bent as to engage said plate to form tension-producing abutments when the detent-engaging member is 110 in engagement with said detents.

3. A bow holder comprising a base plate provided with spaced apart ears and spaced apart detents, and a clasp formed of a single wire bent at its middle portion to form a transverse detent-engaging member and parallel resilient arches, the ends of said arches opposite said detent-engaging member being pivotally mounted in said ears.

4. A head dress retainer comprising a body portion having laterally extending upwardly turned ears on one side and a pair of laterally extending upturned hooks on its opposite side and a ribbon retaining wire

loop having two arms connected by a bridge the ends of said arms being hinged in said ears and its bridge portion being adapted to engage said hooks, and means on its lower side for releasably engaging the hair of the wearer.

In testimony whereof I have affixed my signature, in presence of two witnesses.

FREDERICK F. HASKELL.
